UNITED STATES PATENT OFFICE

95,483

DESIGN FOR A HAND BAG OR THE LIKE

Benjamin Blacher, Providence, R. I., assignor to Blacher Brothers, Providence, R. I., a partnership composed of Benjamin Blacher and Harry Blacher

Application May 27, 1933, Serial No. 48,223

Term of patent 3½ years

To all whom it may concern:

Be it known that I, Benjamin Blacher, a citizen of the United States, residing at 549 Wayland Avenue, in the city of Providence, county of Providence, and State of Rhode Island, have invented a new, original, and ornamental Design for a Handbag or the like, of which the following is a specification, reference being had to the accompanying drawing, forming a part thereof, in which:

Fig. 1 is a front view of the handbag;
Fig. 2 is a reverse view of the handbag; and
Fig. 3 is an end view of the same.

I claim:—

The ornamental design for a handbag or the like, substantially as shown.

BENJAMIN BLACHER.
